J. E. CLOUTIER,
SLIDE CARRIER,
FILED MAY 14, 1921.

UNITED STATES PATENT OFFICE.

JAMES EDWARD CLOUTIER, OF GRACEVILLE, MINNESOTA.

SLIDE CARRIER.

Application filed May 14, 1921. Serial No. 469,460.

To all whom it may concern:

Be it known that I, JAMES EDWARD CLOUTIER, a citizen of the United States, residing at Graceville, in the county of Big Stone and State of Minnesota, have invented certain new and useful Improvements in Slide Carriers, of which the following is a specification, reference being had to the accompanying drawings.

10 This invention relates to slide carriers and has for its object to provide a device of this character adapted to properly position a slide before a light projecting machine.

15 It is the primary object of the invention to provide a carrier of this character capable of holding a plurality of illustrating slides and wherein the slides may be quickly brought into position by merely rotating the carrier.

20 It is another object of the invention to provide a carrier of this character capable of being applied to conventional types of light projecting machines and wherein means are provided for attachment to the supporting shaft of the carrier for locking the carrier when the slides thereof are properly positioned before the light projecting lens of the machine.

25 It is still a further object of the invention to provide a carrier of this character wherein any number of slides may be used, the slides being changed after the carrier has made one complete revolution, without requiring the carrier to be disengaged from the machine or interfering with the slide that is in use.

30 With these and other objects in view the invention consists in the improved construction and arrangement of parts to be herein-40 after more particularly described, fully claimed and illustrated in the accompanying drawings in which:—

35 Figure 1 is a plan view of a slide carrier constructed in accordance with an embodiment of the invention,

40 Figure 2 is an end elevation,

45 Figure 3 is a sectional view taken on the line 3—3 of Figure 1, and

50 Figure 4 is a detailed view of the holding spring.

55 Referring to the drawings 5 designates a body member or plate preferably circular in form and having a bead 6 provided at its outer edge to reinforce the plate. A plurality of openings 7 are provided in the plate, said openings being preferably rec-

tangular and are so positioned that they substantially radiate from the center of the plate so that when one of the openings is brought before the lens of the light projecting machine the side of the opening will be parallel to the vertical. 60

Each of the openings 7 is provided with guide members 8, all of said guide members being disposed on the same side of the body 65 member. The guide members extend down both sides of the openings and across the end of the openings adjacent the center of the body member. The ends of the openings adjacent the periphery of the plate are 70 unobstructed to provide an entrance to the guide members.

In order to prevent accidental disengagement of the slides from the openings, an opening 9 is provided in the body member 75 between the periphery of the body member and the adjacent end of the opening. A retaining spring 10 is secured at one end to one side face of the body member, passed over the periphery of the body member, and 80 through the opening 9. The end of the spring is extended at right angles to prevent accidental disengagement of the end of the spring from the opening. By this means the spring may be compressed to permit the 85 insertion of the slide and when released returns to its former position and engages the outer end of the slide.

The central portion of the body member 5 is provided with an opening 11 in which 90 a sleeve 12 is mounted, said sleeve being secured to the body member, a portion thereof projecting on both sides of the body member. This sleeve is intended to receive a supporting shaft A which is carried by the 95 light projecting machine (not shown). Secured to and projecting from one side face of the body member 5 is a collar 13, said collar being disposed in spaced relation to the sleeve 12 and being formed with many 100 sides, each side being disposed substantially parallel to the end of the adjacent opening. A plurality of recesses 14 are provided in the outer edge of the collar, said recesses being disposed substantially at the intermediate portions of each of the sides of the collar. 105

In order to maintain the opening in the proper position before the rays of the light projecting machine there is provided a novel 110 holding means consisting of a holding finger 15 constructed from a single length of re-

silent material. The end 16 of the finger is formed into an eye adapted to receive the end of the shaft A. The intermediate portion of the finger is substantially crimped or bent to increase the resiliency thereof, the end 17 of the finger projecting over and beyond the edge of the collar 13. In the application of the finger, the end of the shaft A is provided with a nut 18 and the eye or 10 end 16 of the finger is engaged with the shaft. A second nut 19 is threaded on the shaft so as to firmly clamp the end 16 of the finger to the shaft and between the nuts 18 and 19. It will be noted that the crimped 15 portion of the finger is disposed at all times inwardly of the collar so that there is no danger of objects coming in contact with the crimped portion and thereby interfering with the holding power of the finger. 20 In use, after the slides are applied to the carrier, the stem is rotated on the shaft A so as to bring the desired slide into position. The slide is maintained in the proper position by contact of the finger 15 with the wall 25 of the adjacent recess 14. It is of course obvious that the resiliency of the finger 15 does not interfere with the carrier being rotated when it is desired to change the slide, as the end 17 of the finger projects 30 beyond the collar, and may be grasped by the operator so as to disengage the finger from the collar and permit the carrier or body member to be rotated without causing the same to be locked when the recesses pass 35 the finger 15.

From the foregoing it will be readily seen that this invention provides a novel form of slide carrier simple in construction and one that may be readily applied to any light 40 projecting machine. Another important feature of this carrier is that it is not nec-

essary to reverse the slide when applying the same to the carrier, as the slide may be inserted in the guides in an upright position at the top of the carrier so that when the carrier is rotated the slide will be reversed or turned when the portion of the carrier holding the slide reaches the light projecting lens. 45

What is claimed is:—

1. A slide carrier of the character described embodying a supporting shaft, a body member mounted on the shaft, a collar carried by the body member and surrounding the shaft in spaced relation thereto, said 55 collar having a plurality of recesses, and a resilient holding member secured to the shaft and frictionally engaging the collar, said holding member being arranged to alternately enter the recesses upon movement 60 of the body member on the shaft to prevent movement of the body member in either direction.

2. A slide carrier of the character described embodying a supporting shaft, a 65 body member rotatably mounted on the shaft, said body member having a plurality of substantially radiating slide openings, a collar secured to one side face of the body member, the outer surface of said collar being disposed substantially parallel to the end of the adjacent opening, a resilient holding finger secured to the shaft, said holding finger extending inwardly of and over the edge of the collar and arranged to 70 frictionally engage the edge to position said openings centrally of the finger and lock the body member to the shaft.

In testimony whereof I hereunto affix my signature.

JAMES EDWARD CLOUTIER.
